ATTORNEY'S

Patented Sept. 23, 1924.

UNITED STATES PATENT OFFICE.

BENJAMIN F. FITCH, OF EVANSTON, ILLINOIS.

HOISTING CRADLE.

Application filed April 22, 1921. Serial No. 463,531.

To all whom it may concern:

Be it known that I, BENJAMIN F. FITCH, a citizen of the United States, residing at Evanston, in the county of Cook and State 5 of Illinois, have invented a certain new and useful Improvement in Hoisting Cradles, of which the following is a full, clear, and exact description, reference being had to the accompanying drawings.

10 This invention relates to a hoisting mechanism and is primarily concerned with the construction of load engaging means adapted for use in connection with the hoisting and conveying of freight containers.

15 My mechanism is arranged to be employed in a system for handling package freight, wherein the freight may be stored within a container, such as an automobile body, for transportation of a unit, from one 20 distributing point to another. My invention is adapted to be utilized with a suitable form of overhead traveling crane, particularly one having four depending flexible lifting members.

25 In effecting the transfer for example, of a removable body to and from an automobile truck, I have provided a cradle which is so arranged that it may be lowered over the body and be readily moved into engagement therewith. As a loaded truck, for instance, arrives at a station, it is possible for 30 the mechanism to pick up a loaded body from the truck without requiring the services of anyone other than the crane operator, and to transport the body and then deposit it in a suitable position for storage or unloading. As soon as the suspended body 35 is deposited upon a support, such as a station platform, a further downward movement of the hoisting cables effects an automatic disengagement between the cradle and the load.

40 In carrying out my invention, I employ a cradle of articulated form, which is provided with load engaging portions extending at each side thereof, and is further provided with hinged intermediate portions which are employed for moving the load engaging portions inwardly. This inward motion is sufficient to bring the load engaging portions beneath rigid members secured to the sides of the body, so that an upward movement, effected by the lifting cables, 45 may cause the load to be engaged and there- 50 after raised.

The means for accomplishing the above features will be more fully set forth in the following description, which relates to the drawings, and the essential characteristics of my invention will be set forth in the 60 claims.

In the drawings, Fig. 1 is an elevation of an automobile truck body beneath an overhead hoisting mechanism having a cradle embodying features of my invention; Fig. 2 is a perspective view of the cradle and load engaging mechanism; Fig. 3 is an enlarged end view of one corner of the cradle; Fig. 4 is a plan of the corner shown in Fig. 3; Figs. 5 and 6 represent two positions of 70 the hinged members on the cradle when the cradle is in load engaging and disengaging positions, respectively.

Designating the parts shown in the drawings by the use of reference characters, 10 75 and 11 represent supporting columns carrying a set of overhead tracks 12 and 13 on which a crane, designated generally at 14, is adapted to travel. Suitable hoisting mechanism is positioned on the crane, and the 80 embodiment shown comprises a motor 15, hoisting drum 16 and cables 17. Each of the cables are shown as having one end thereof secured to the hoisting drum and as having the other end thereof passing 85 downwardly over the load supporting sheaves 18 and secured to the structural members of the crane.

My invention is concerned with the construction of a cradle that is adapted to be 90 suspended by the hoisting cables and to be brought into engagement with a load. In Fig. 1 such a load is represented as a removable automobile body 19, which is carried on the truck 9 and is removably secured 95 thereto.

Referring now to Fig. 2, the numeral 20 represents suitable downwardly projecting hooked members or side bars which extend lengthwise of the body and are secured thereto adjacent the upper edge thereof. These body hooks may be in the form of structural members, or they may be short members positioned at separated intervals 100 along walls of the body, in accordance with the construction of the body frame. The body frame preferably has suitable side trussing, as indicated at 21, so that the stresses of the load on the body floor may 105 be satisfactorily distributed to the top of 110

- the body where the trough-shaped members 20 are located. It will thus be seen that the cradle comprises an open articulated frame that is hinged along the middle portion thereof and provided with suitable load engaging members, which are arranged to be moved laterally by vertical movement of the intermediate members or end bars 27 and 28.
- 10 To strengthen the cradle and to provide a convenient weight for moving the hinged intermediate members, I provide a connecting member 35 which extends between the hinged pintles 32 and 33, and between the two sets of hinged members. This member 35 is preferably an I-beam that possesses sufficient weight to force the hinged pintles 32 and 33 downwardly, and thereby force the bars 25 outwardly when the cradle is suspended by the cable 17.
- 15 To raise the load, I have shown a sheave 18, as positioned adjacent each corner of the cradle, and as supported at 36 in the bracket 31. A convenient means for retaining the sheave in such position is to provide reinforcing plates 37 and 38, which are positioned on either side of the sheave, and arranged to be rigidly secured to the bar 25, on the side opposite the reinforcing member 26.
- 20 I have found that this construction permits the employment of structural shapes, and at the same time provides sufficient rigidity to support a loaded body.
- 25 The cradle, which is arranged to be carried by the supporting cables for engaging a load, comprises a pair of longitudinal hooked bars 25, which are preferably rolled structural shapes having the lowermost end thereof curved inwardly and upwardly so as to engage beneath the trough-shaped members 20. Due to a small contact area between complementary trough-shaped members 20 and 25, I provide a stiffening member 26 which may extend longitudinally of the bars 25 and be rigidly secured thereto. This reinforcing member is shown as a channel beam having outwardly facing flanges, and positioned adjacent the uppermost edge of the members 25.
- 30 Intermediate the bars 25 and preferably adjacent the ends thereof, I provide as stated above, intermediate members or bars 27 and 28, which comprise upper and lower members respectively of a parallel linkage system. These members, or links, are shown as having one end thereof pivoted at 29 and 30 respectively to a bracket 31; and as having the other ends thereof pivoted together at 32 and 33, thereby forming a hinged joint.
- 35 Each hinged joint 32 may be attached to the lower end of a cable 40, which cable is arranged to be operated independently of the lifting cables, and to control the height of the hinged joints. The cables 40 may extend across the top of the crane and be connected to a single cable 41, which single cable preferably extends downwardly so as to be within reach of the operator. Under the arrangement shown, a downward pull on the cable 41 effects an upward movement of the cables 40, and a consequent upward movement of the hinged joints, while a release of the cable 41 permits a lowering of the cable 40 with consequent lowering of the hinged joint.
- 40 Referring now to Fig. 6, it will be seen that the cradle is positioned directly above a load and that the engaging bars 25 are directly beneath the trough-shaped members 20. In this position, the arms 27, 28 are extended and the cradle is suspended by the hoisting cables 17, from an overhead crane, and is held in such outspread position by the weight of the gravity member 35. To cause the bars 25 to move inwardly for engaging the load, the buckling cables 40 are raised, whereupon the bars are moved inwardly and are automatically positioned beneath the trough-shaped member on the body. Due to the arrangement of the intermediate members in the form of a parallel linkage system, the load engaging bars 25 move inwardly, and while so moving remain disposed in a plane, parallel to their original position.
- 45 After the cradle bars are positioned beneath the trough-shaped members on the body, while the operator maintains the pull on the buckling cables, thereby exerting a lifting force upon the hinged portions, the hoisting cables are raised, and the trough shaped bars on the cradle are brought into engagement with those on the body. As soon as the body is raised, the load is carried by the longitudinal bars of the cradle without the aforementioned links being subjected to any of the lifting stresses. As soon as the load comes onto the cradle the pull on the buckling cable may be relaxed, as the parts remain in the position shown in Fig. 5.
- 50 Assuming that a body has been raised and transported to a suitable position, either for storing or unloading, then the lowering of the cables 17 is continued until such body is positioned on the support. A further downward movement of the supporting cables permits the connecting member 35 to depress the hinged pintles 32 and 33, and thereby to spread the trough-shaped bars 25, so as to disengage them from the trough-shaped members 20 on the body. This disengagement is automatically effected by the weight of the connecting member 35 as soon as the load is removed from the hoisting cables.
- 55 In the operation of a system embodying a series of removable bodies, it will be seen that the employment of a hoisting mechanism, having a load engaging cradle constructed according to my invention, provides an efficient means for facilitating the handling of the loaded containers, and enables such handling to be accomplished in a mini-

5   mum period of time. By the employment of my invention, the labor requirements are quite materially reduced, it being possible to operate the raising and buckling cables with the services of only one operator.

10   A cradle constructed according to my invention is, of course, adapted for engaging and thereafter raising a plurality of containers simultaneously by aligning such containers and engaging them as a unit by cradle bars which are substantially as long as the set of containers.

15   It may be noted that this application is a continuation in part, of Patent No. 1,433,993 issued to me October 31, 1922. A system for transporting freight by means of truck bodies is set forth in such co-pending application, and reference may be had thereto for a description of such a system.

20   Having thus described my invention, I claim:

1. In a hoisting mechanism, the combination with an articulated cradle hinged at each end, and adapted to engage a load, 25 means for raising and lowering the cradle, and means operable independently of the raising and lowering means for engaging the hinged portions, and for buckling them to bring the cradle into position to engage and 30 raise a load.

2. The combination of a supporting frame, cables depending therefrom, a hinged, substantially rectangular cradle carried near the corners thereof by said cables, 35 and means operable independently of said cables for engaging the hinge of the cradle to bring the cradle into position to engage a load.

3. A cradle adapted to engage a removable automobile body, and comprising load supporting side bars, elevating cables secured directly over the side bars, and end bars secured to the side bars and hinged together.

45   4. A cradle comprising a rectangular frame having a pair of hooked side bars adapted to engage a load, and a pair of end bars hinged at the middle, and intermediate said side bars, means for raising the 50 side bars whereby the load may be lifted, and other means for moving the end bars whereby the load may be engaged or released.

55   5. The combination of a frame, a pair of cables depending therefrom, a cradle connected with the cables, said cradle comprising side bars and end bars, the end bars being hinged intermediate the side bars, and a cable pivotally connected with each of said 60 hinges whereby the hinge may be raised to cause the side bars to engage the load.

65   6. The combination of a supporting frame, four cables depending therefrom, a load engaging hinged cradle in the form of an open frame carried by said cables, two

on one side and two on the other, means for folding the cradle about the hinged joint, and means for simultaneously winding in or paying out said cables.

7. The combination of a supporting frame, four cables depending therefrom, a cradle in the form of an open frame intermediate hinged and carried by said cables, means for simultaneously winding in or paying out said cables, and means for moving the hinge of the cradle for causing portions thereof to swing inwardly to engage a load.

8. The combination of a frame, four cables depending therefrom, a hinged load engaging cradle carried by said cables, two 80 on one side and two on another, means for simultaneously winding in or paying out said cables, and means for raising the hinge of the cradle to cause its side portions to swing inwardly to engage a load.

85   9. The combination of a frame, winding mechanism thereon, four cables depending from the winding mechanism and adapted to be simultaneously raised or lowered by it, and a cradle supported by the cables and 90 comprising side bars and a pair of end bars connected with the side bars and hinged to each other.

10. The combination of a frame, winding mechanism thereon, cables depending from 95 the winding mechanism and adapted to be raised or lowered by it, a substantially rectangular cradle supported adjacent the corners thereof by the cables and comprising side bars and a pair of end bars, said end bars 100 being connected with the side bars and hinged to each other, and cables connected with the hinges of the cradle to draw said hinges upwardly for causing the load engaging sides to swing inwardly.

105   11. The combination of a frame, a cradle suspended therefrom and comprising a pair of hooked side bars and a pair of end bars connected with the side bars and hinged to each other, and a member extending between 110 the end bars and connected therewith adjacent to the hinge, said member tending to depress the hinge.

115   12. The combination with a removable automobile body having rigidly downwardly extending projections on the walls and adjacent the top thereof, of a hoisting mechanism comprising a rectangular frame having a pair of oscillatable side bars adapted to be dropped over said sides for engaging the under sides of said projections, sheaves projecting above the side bars and cables extending beneath the sheaves.

120   13. The combination with a removable automobile body having rigidly downwardly extending projections on its sides, of a hoisting mechanism having a cradle comprising a substantially rectangular frame having side bars adapted to be dropped over said sides, 125 sheaves positioned adjacent the corners of

- the frame, cables extending beneath the sheaves for raising the frame and means for causing the side bars to swing inwardly to engage the under sides of said projections.
14. The combination with a removable automobile body having projections on its side, of hooked side bars adapted to engage said projections, end bars hinged immediately and connecting said side bars, means adjacent the hinged connections for depressing the end bars, and raising means connected with the side bars.
15. The combination with a removable automobile body having projections on its sides, of a cradle comprising a pair of side bars adapted to engage said projections, and end bars having one end thereof connected with the side bars and the other end thereof hinged intermediate said side bars, means connected with the side bars for raising the cradle, means tending to depress said end bars, and means operable independently of the raising means for buckling the hinges of the cradle.
16. The combination with a removable automobile body having projections on its sides, of a frame having cables depending therefrom, a cradle carried by some of the cables and comprising a pair of hooked side bars adapted to engage said projections, and means for moving the side bars outwardly, said means being connected with the other of said cables.
17. The combination with a removable automobile body having projections on its sides, of a cradle comprising a pair of side bars adapted to engage said projections, and end bars connected to the side bars and hinged to each other, means for raising the cradle, and means independent of the raising means for buckling the hinges of the cradle.
18. The combination with a removable automobile body having projections on its sides, of a cradle comprising a pair of hooked side bars adapted to engage said projections, and bars connected to the side bars and hinged to each other, means tending to depress said hinged bars, and means for raising the hinges of the cradle.
19. The combination with a removable automobile body having downwardly extending projections on its sides, of side bars having upwardly extending inner edges, and adapted to engage beneath said projections, and raising cables extending vertically from the side bars.
20. The combination with a removable automobile body having downwardly extending projections on its sides, of a hoisting mechanism having a cradle adapted to be dropped over said sides, means attached near the corners of the cradle for exerting a vertical raising force thereon, and means attached to the middle of the cradle for buckling the cradle to cause engagement with the under sides of said projections.
21. The combination with a removable automobile body having downwardly extending projections on its sides, of a cradle comprising a pair of hooked side bars adapted to engage said projections and end bars connected to the side bars and hinged to each other, means for constantly urging the hinged end portions downwardly, and means for raising the hinges of the cradle.
22. The combination with a removable automobile body having projections on its sides, of a hoisting mechanism, a cradle suspended therefrom and comprising a pair of side bars adapted to engage said projections, and end bars connected to the side bars and hinged to each other, a weight tending to depress said hinged side bars, and cables for elevating the hinges.
23. The combination with a removable automobile body having downwardly facing hooked members on its sides adjacent to the top, of oscillatable raising bars extending lengthwise of the body, said bars comprising members that extend upwardly and inwardly to engage beneath said hooked members, and means for raising said bars, while maintaining them parallel.
24. The combination with a removable automobile body having downwardly facing hooked members on its sides adjacent to the top and longitudinal trough-shaped bars adapted to hook upwardly into engagement with the side hooks in the body, and means for raising the trough shaped bars, while maintaining them parallel.
25. The combination with a removable automobile body having downwardly extending hooked members on its sides adjacent to the top, and a raising cradle having upwardly extending hooked members adapted to engage beneath those on the body, said cradle members comprising longitudinal trough-shaped bars and end bars connected with the longitudinal bars and hinged to each other.
26. The combination with a removable automobile body having downwardly extending longitudinally arranged hooked members at its sides adjacent to the top, a raising cradle consisting of longitudinal trough-shaped bars adapted to engage beneath the hooked members on the body, and end bars connected to the longitudinal bars and hinged to each other, four raising cables connected with said longitudinal bars adjacent to their respective ends, and two cables connected with the end bars adjacent to their hinges to buckle the cradle and swing its side bars inwardly.
27. The combination with a device to be lifted, having downwardly facing hooked members and trough-shaped bars adapted

to hook upwardly into engagement with the said members, and cables operatively connected to the trough-shaped bars and extending thereabove for raising the bars, whereby lifting stresses are transmitted from a load directly to the cables.

28. The combination with a device to be lifted having downwardly facing hooked members, bars extending upwardly and inwardly to engage beneath said hooked members, means extending directly over said bars for raising them, and other means for shifting said bars.

29. In a hoisting mechanism, the combination of an articulated cradle adapted to engage a load, means for raising and lowering the cradle, and means comprising a four-bar parallel motion linkage for buckling the cradle to cause it to come into position to engage the load.

30. A cradle comprising side bars provided with means for supporting a load, spreading bars secured to the side bars and hinged together, gravitational means extending between the hinged connections of the spreading bars and normally tending to extend said spreading bars, and means for buckling said spreading bars, whereby the side bars are caused to move inwardly while remaining parallel to themselves.

31. In combination, a load having downwardly extending projections on the sides thereof, a cradle having side bars provided with inwardly and upwardly extending projections and having parallel linkage means for moving the side bars inwardly, and other means for raising the cradle to cause the projections thereof to engage with the projections on the load.

32. A cradle comprising a pair of side bars adapted to engage a load, a pair of articulated members connected to the side bars, and a longitudinal gravitational member connecting said articulated members intermediate their points of articulation.

33. The combination with an automobile body having downwardly extending hooked

members on its sides, of a cradle having upwardly facing trough-shaped members adapted to engage beneath said body members and having hinged separating bars pivoted at one end to the trough-shaped bars, said hinged bars comprising parallel links disposed one above the other, cables attached to the trough-shaped members for raising the cradle and other cables attached to the hinged bars for moving the trough-shaped members inwardly to engage a body.

34. The combination with an automobile body having downwardly extending hooked members on its sides, of a cradle having trough-shaped members adapted to engage beneath said body members, and having hinged separating bars pivoted at one end to the trough-shaped bars, said hinged bars comprising parallel links disposed one above the other, a member extending between the hinged bars and tending to depress them for causing the hook shaped bars to move away from each other, and cables for raising said member to move the bars inwardly.

35. In a hoisting mechanism, the combination of an articulated cradle adapted to engage a load, said cradle comprising upwardly facing trough-shaped side bars, and mechanism for spreading the same comprising a longitudinal bar and four sets of four-bar linkage connecting it with the side bars, and four raising cables connected to the side bars independently of the linkage system.

36. The combination of a pair of hooked side bars adapted to engage a load, four sheaves carried two by each bar, and raising cables extending beneath the sheaves.

37. The combination of a pair of hooked side bars adapted to engage a load, sheaves carried by the side bars, cables extending beneath the sheaves for raising a load, and means operable independently of the cables for moving the side bars laterally with respect to each other.

In testimony whereof, I hereunto affix my signature.

BENJAMIN F. FITCH.
